UNITED STATES PATENT OFFICE.

MARTIN KENNEDY, OF CHICAGO, ILLINOIS, ASSIGNOR OF ONE-HALF TO WILLIAM RENSHAW, OF CHICAGO, ILLINOIS.

METAL-WORKING MACHINE.

1,034,466.

Specification of Letters Patent.

Patented Aug. 6, 1912.

Application filed November 22, 1909. Serial No. 529,433.

To all whom it may concern:

Be it known that I, MARTIN KENNEDY, a citizen of the United States, residing at Chicago, in the county of Cook and State of Illinois, have invented certain new and useful Improvements in Metal-Working Machines, of which the following is a specification.

My invention relates to a machine for bending, forging, welding, shaping and otherwise operating upon metal, which might, therefore, be aptly termed a mechanical blacksmith, since it is intended to accomplish those operations which are ordinarily performed by the hand labor of the blacksmith. A machine of this sort is shown in my Patent No. 644,294, granted February 27, 1900. The object of the present invention is to provide certain improvements upon the machine shown in the patent referred to, relating particularly to the control of the fluid pressure by which the operative parts of the machine are actuated in their movements whereby the operation of the machine is facilitated.

The invention is illustrated in the accompanying drawings, wherein—

Figure 1 is a plan view of one form of machine embodying my present invention. Fig. 2 a side elevation of the same taken at the right hand side of the machine, as shown in Fig. 1. Fig. 3 a vertical sectional view on line 3—3 of Fig. 1, looking in the direction of the arrows. Fig. 4 a section taken on line 4—4 of Fig. 3, looking in the direction of the arrows. Fig. 5 an elevation of the machine taken from the opposite side. Fig. 6 a side view of one of the controlling valves. Fig. 7 a section on line 7—7 of Fig. 6, looking in the direction of the arrows. Fig. 8 a sectional plan taken on line 8—8 of Fig. 7, and Fig. 9 a plan view of a machine illustrating a modification.

Like characters of reference indicate like parts in the several figures of the drawings.

Referring first to Figs. 1 to 8 inclusive, the operative parts of the machine are arranged upon and secured to a bed-plate composed of two sections 10 and 11 which are supported upon the supports 12, or otherwise, as desired.

The section 11 of the bed-plate is provided with the flanges 13 and parallel thereto, the flanges 14; the flanges 13 being reinforced by the webs 15. Between the

flanges 13, which are rabbeted, is the removable filling block 16 which structure constitutes a stationary die.

Between the pairs of flanges 13 and 14 are the die block 17 and 18, preferably provided at adjacent corners with the rollers 19 and partly covered by the plates 17^a, 18^a plate 17^a being omitted in Fig. 1 to show the parts below it.

The die block 18 is connected to the end 65 of a screw 20 which is threaded through a flange 21 on the bed-plate, the connection between the screw and the die block being one allowing the screw to rotate, so that by means of the screw the die block may be 70 set at any desired position.

On the bed-plate behind die block 17 is a cylinder 22 which is preferably bolted or otherwise firmly secured to the bed-plate, and this cylinder is provided with a piston 75 23 which has a rod 24 having the squared end 25 which extends into a recess in the back of the die block 17, the rod being rigidly secured to the die block by the pin 26 or other suitable means. The head of the 80 cylinder is provided with the usual packing 27.

On the section 10 of the bed-plate is a cylinder 28 provided with the piston 29 having the rod 30 to the end of which is removably secured the tool 31, the character 85 of this tool differing, of course, according to the sort of work being done by the machine.

The pistons 23 and 29 are intended to be moved in each direction by fluid pressure, 90 preferably, by steam. 32 is a steam or other fluid supply pipe having the branches 33 and 34 leading to the steam inlets of the control valves 35 and 36, respectively. Pipes 37 and 38 lead from oppositely arranged outlet ports of valve 35 to the opposite ends of cylinder 22. A corresponding pair of pipes 39 and 39^a lead to the opposite ends of cylinder 28.

A suitable form of control valve is shown 100 in Figs. 6 to 8 inclusive. The casing of this valve 35, for example, is in the form of a truncated cone, closed at opposite ends by the cap-pieces 40 and 41. The valve case is formed with the oppositely arranged 105 steam outlet ports 42 and 43 and the exhaust ports 44 and 45 which connect with exhaust pipes 44^a, 45^a. Within the casing is the valve-piece 46 formed with the central bore 47, with the slots 48 and 49 extending 110

through to the central bore 47 and with the recesses 52 and 53. The cap screw 41 is formed with the port 54, leading to the central bore 47. The casing is formed with a slot 55 through which extends the operating lever 56 of the valve piece.

It will be understood that, supposing the above description to apply to the control valve 35 for controlling the flow of steam to cylinder 22, the pipe 33 will be connected with port 54, and the pipes 37 and 38 with ports 42 and 43. With the valve piece in the position shown in Figs. 7 and 8, the steam which enters the central bore 47 of the valve-piece through pipe 33 and port 54 will pass through port 42 and pipe 37 to the power end of cylinder 22, causing the piston 23 to move the die block 17 toward die block 18. At the same time, the end of cylinder 22 inwardly of the piston 23 will be in communication with the atmosphere or with some suitable place of exhaust through pipe 38, port 43, recess 52 in the valve-piece and exhaust port 45. Now if the lever 56 be moved to its other extreme position, the slot 49 in the valve-piece will be brought into register with port 43, and communication will be opened between the inner or return end of cylinder 22 and the supply of steam. This movement of the valve-piece will close communication between the central bore 47 and port 42, and, consequently, between the supply of steam and the power end of the cylinder, while opening communication between port 42 and exhaust 44, thus allowing the free escape of steam from the outer or power end of the cylinder to the atmosphere or place of exhaust. The piston 23 will, therefore, be moved backwardly. Obviously, by shifting the lever 56 back and forth the die block may be reciprocated on the bed-plate so as to strike a series of blows against any object that may be placed in its path.

By turning the lever 56 to an intermediate position, communication may be cut off between the steam supply and both ends of the cylinder.

It will be understood that the control valve 36 for the cylinder 28 is similarly constructed and operates in the same manner. The two valves are preferably arranged close together, as shown, so that they can be handled by a single operator. If desired, the tool 31 and the die block 17 may be operated simultaneously.

In Fig. 9 I have shown a modified form of apparatus in which the die block 57 corresponding to the die block 18 of the other machine may also be operated by fluid pressure. The block 57 is connected, in the manner above described, to the end of the rod 58 of a piston 59 in a cylinder 60, bolted

to the bed-plate, the opposite ends of this cylinder being connected by pipes 61 and 62 with a control valve 63, of the construction described, to which steam is supplied through a continuation 64 of the branch pipe 33. In this form of machine the object may be operated upon from three sides, or, if desired, one or both of the die blocks may be held against the object being worked upon by the steam pressure. If one of the die blocks be used as a hammer, the other constitutes a cushioned support for the article operated upon.

The machine thus constructed may be used in a great variety of ways for bending, shaping, forging, welding and riveting iron and steel. The nature of the work will determine the shape and character of the tool 31. The shape and character of the die blocks may likewise be varied in accordance with the operations which they assist in performing. These latter members I have termed "die blocks", but it will be clear from the above description that they or one of them may be used to perform the function of a hammer. As the machine is susceptible of considerable change in the shape and construction of its parts without in general changing its purpose and function, I do not limit myself to the particular devices, arrangements and constructions shown.

I claim:

In a machine for operating upon metal, the combination with a bed plate, of a cylinder secured thereto, a piston in said cylinder, a second cylinder at right angles to the first named cylinder, a piston therein, a metal working implement connected with each of said pistons; a fluid supply pipe, a controlling device for each cylinder comprising a casing having an inlet port, two outlet ports and two exhaust ports, and a valve, branches from the fluid supply pipe to the inlet port of each of said valve casings, and pipes leading from the outlet ports of each valve casing to the opposite ends of the corresponding cylinders; each of said valves being adapted in one position to put the inlet port of the controlling device of the corresponding cylinder in communication with one end of said cylinder through one of said outlet ports and the other end of the cylinder in communication with the exhaust port through the other outlet port, and in another position to reverse these connections so that the first named end of the cylinder exhausts and the other end receives fluid from said fluid supply pipe.

MARTIN KENNEDY.
